UNITED STATES PATENT OFFICE.

NED EASTMAN BARNES, OF WILLIS, TEXAS.

RAILWAY-RAIL BRACE.

1,190,083.

Specification of Letters Patent.

Patented July 4, 1916.

Application filed April 9, 1915. Serial No. 20,143.

To all whom it may concern:

Be it known that I, NED EASTMAN BARNES, a citizen of the United States, residing at Willis, in the county of Montgomery and State of Texas, have invented certain new and useful Improvements in a Railway-Rail Brace, of which the following is a specification.

This invention relates to new and useful improvements in a rail-way rail brace.

The object of the invention is to provide a brace of the character described, which is designed particularly to be used on curves of rail-way tracks, and which ties the rails in fixed position relative to each other, so as to prevent spreading of said rails. The brace however, may also be used on straight tracks, and when employed, a less number of ties will be necessary.

When applied to the rails at the joints formed by the abutting ends of adjacent rails, the brace acts also as a substitute for the ordinary fish-plates, now in common use for securing said abutting rail-ends together.

With the above and other objects in view, the invention has particular relation to certain novel features of construction, arrangement of parts and use, an example of which is given in this specification and illustrated in the accompanying drawings, wherein:

Figure 1, is a side elevation of the brace, as applied to the rails. Fig. 2, is a side elevation thereof, showing a modified form of the brace. Fig. 3, is an enlarged vertical sectional view of the form shown in Fig. 2, and, Fig. 4, is an enlarged vertical sectional view of the form shown in Fig. 1.

Referring now more particularly to the drawings, wherein like numerals of reference designate similar parts in each of the figures, the numerals 1 and 2, refer, respectively, to blocks formed of metal or other suitable material, arranged underneath the respective rails 3 and 4. The outer edges of these respective blocks have the braces 5 and 6, respectively, integral therewith, which fit over the outer flanges of the respective rails, and whose free edges rest against the outer sides of the rail webs. The blocks, 1 and 2, are held in fixed position relative to each other, by means of the tie-rod 7, whose ends are threaded and pass through central transverse apertures in said respective blocks, and threaded upon the respective ends of said rod are the jam-nuts 8 and 9,

which lock the blocks against detachment from the rod.

Brace plates 10 and 11, are provided, which fit against the inner sides of the respective blocks 1 and 2, and whose upper or free edges are bent over against the inner flanges of the respective rails 3 and 4. The rod 7, passes through these plates, and they are secured in position against the corresponding blocks by means of the lock nuts 12 and 13.

In Figs. 2 and 3, I have shown a modified form of the brace, wherein the block 1', is shown substantially similar to the block 1, but the brace plate 10', is shown integral therewith. Before this block is placed in position on the rail, the plate 10', is curved outwardly, as shown in dotted lines, in Figs. 2 and 3, and after the block is placed, this plate is bent over so as to engage the inner rail-flange, as shown. In other respects, the form shown in Figs. 2 and 3, is similar to that shown in Figs. 1 and 4, excepting that the tie-rod 7', is integral with the block 1', and has the fixed annular shoulder 13', which holds the brace plate 11', in position; and the jam-nut 9', is held locked against the block 2', by means of the lock nut 14.

In case the rails are used as electrical conductors, they may be insulated from the rail-brace by interposing suitable insulating material, between the rail and brace, as shown in the figures.

Ordinarily three of the braces will be employed for each rail length, one at the center of the rail and one midway between the center and the rail end on each side. However, a greater or less number may be employed, the number being determined by the traffic over the road and the angle of the curves, thereof.

While I have shown only two forms of the device, it is obvious that the mechanical structure may be varied, without departing from the principle of the invention, and I hereby reserve the right to make such structural changes as may be found necessary, so long as I keep within the scope of the appended claims.

What I claim is:

1. In a railway brace, brace blocks engaging against the outer sides of the respective rails of a track and having undercut grooves in which the outer rail flanges, respectively, fit, a tie rod attached to one of said blocks

at one end and whose other end has an annular shoulder integral therewith, against which the corresponding block is located and by means of which it is fixed upon said rod and an adjustable brace plate carried by each block and engaging over the inner flanges of the respective rails.

2. In a railway rail brace, brace blocks engaging against the outer sides of the respective rails of a track and upon which said rails rest, and having undercut grooves in which the outer rail flanges, respectively, fit, and a tie rod, one end of which extends through one block and the other being rigid 15 with the other block, nuts secured upon the outer end of said rod and securing said rod

against detachment therefrom, a brace plate through which one end of said rod extends and another brace plate with which the other end is rigid engaging over the inner flanges of the respective rails and a shoulder on said rod against which the inner side of one of said plates rests when in normal position. 20

In testimony whereof I have signed my name to this specification in the presence of 25 two subscribing witnesses.

NED EASTMAN BARNES.
